Inventor:

Joseph Komorous,
By Dyerforth, Lee, Cutton and Wiles.
H. T. S.

UNITED STATES PATENT OFFICE.

JOSEPH KOMOROUS, OF CHICAGO, ILLINOIS, ASSIGNOR TO PARISIAN NOVELTY COMPANY, OF CHICAGO, ILLINOIS, A CORPORATION OF ILLINOIS.

POWDER-RECEPTACLE.

1,231,384.

Specification of Letters Patent. Patented June 26, 1917.

Application filed April 25, 1916. Serial No. 93,458.

To all whom it may concern:

Be it known that I, JOSEPH KOMOROUS, a citizen of the United States, residing at Chicago, in the county of Cook and State 5 of Illinois, have invented a new and useful Improvement in Powder-Receptacles, of which the following is a specification.

My invention relates more particularly to improvements in so-called vanity cases, 10 wherein provision is made for storing face powder, or the like material, and powder-puffs, and usually of a size adapting them to be carried in a lady's pocket-book, or hand-bag, and my object is to provide a 15 novel, simple and economical form of vanity-case.

Referring to the accompanying drawing, Figure 1 is a view in side elevation of a vanity-case constructed in accordance with 20 my invention, the cover of the case being shown separated therefrom. Fig. 2 is a view of the mirror-equipped face of the cover. Fig. 3 is a plan view of the body of the case with the cover removed. Fig. 25 4 is an enlarged view in sectional elevation of the case with certain of the parts shown in disassembled but related, positions, this view showing the form of the parts of the body of the case before the assembling and 30 securing operations; and Fig. 5 is a similar view of the case after the parts have been assembled, and showing the cover in position thereon.

The case is formed of a body-portion 6 25 and a cover 7, these parts being formed of any suitable material and in any desirable way, but preferably formed of metal, or other desirable sheet-material, and preferably covered, at least in part, with a material such as celluloid.

The body 6 is formed of a dish-shaped member 8 having an annular flange 9 about its periphery, over which the cover 10 for the exposed surfaces of the member 8, extends, and is crimped into place, this cover, where used, preferably being celluloid, and the member 8, by preference, being slightly dished at the portion thereof bounded by the base of the flange 9, as shown; a band-member 11 which extends at an angle to the base-member 8 and forms a side of the case and is held in this position by engagement with the bottom member 8, as herein-after described, and a diaphragm 12 located 55 in the space provided between the bottom

member 8 and the band-member 11, and dividing it into a lower compartment 13 for powder, and an upper compartment 14 for a powder-puff, such as is usually provided in constructions of this character. 60

The diaphragm 12 in the particular construction illustrated is formed as a part integral with the band-section 11, as represented in Fig. 4, this band-section and diaphragm being preferably pressed from 65 sheet-metal. The diaphragm 12 is preferably upwardly offset, as represented, to cooperate with the bottom member 8, in providing the space 13 of the desirable volume, the diaphragm 12 containing an opening 15 70 for a purpose hereinafter described.

The band-member 11 is provided about its periphery and closely adjacent to the end thereof at which it joins to the edges of the diaphragm 12, with an annular groove 16, preferably pressed therein during the operation of shaping the combined band-section and diaphragm. The groove 16 is provided for the purpose of forming an interlock with the outer edge of the 75 flange 9, with which this portion of the band 11 telescopes, as shown in Fig. 5, the flange 9 being contracted to extend into the groove 16 after these parts have been telescoped as described, by an operation well known in 80 the art, thus causing the parts described to be firmly secured together in a position for 85 affording the two compartments 13 and 14.

The cover 7 may be of any suitable construction, it being preferred, however, to 90 construct it as shown in the drawings, namely, by forming it of a disk 17 having an annular flange 18, this disk being preferably covered by any suitable material, as, for example, celluloid, as represented at 95 19, and a flanged ring 20 which snugly fits against the inner periphery of the member 17 and is shaped to hold a mirror 21 in place, this cover in the preferred construction shown, being adapted to telescope with 100 the outer end of the band 11 and be releasably held thereto by springing over nubs 11^a on the outer surface of the band-section 11, as represented.

The opening 15 in the diaphragm 12 105 serves, in the particular construction shown, as an opening through which the powder compartment 13 may be charged with powder, and as an opening through which the powder may be sifted for use, it being 110

preferred that means be provided for regulating the closure of this opening, a description of the means illustrated and those which I prefer to employ being as follows:
5 A disk 23 arranged concentric with the diaphragm 12, is rotatably confined thereon, as through the medium of an eyelet 24 arranged concentric with these members, the disk 23 containing a relatively large opening 25 and a series of relatively small perforations 26 disposed in different angular positions relative to the pivotal point of the disk, and so arranged that either the opening 25 or the series of openings 26 may be
10 moved into registration with the opening 15, or a blank part of the disk 23 moved into registration with this opening. The opening 25 is provided for registration with the opening 15 to permit the compartment 13 to be charged with powder. The perforations 26 are provided to enable the powder to be sifted from the compartment 13, and the unperforated portion of the disk 23 serves, when superposed over the opening 15, to close the
15 latter and prevent spilling of the powder, the user merely by rotating the disk 23 on the diaphragm 12, which may be more readily accomplished by reason of the provision of the button 12^a struck up from the diaphragm, effecting the above stated registrations as desired.

While I have illustrated and described a particular construction embodying my invention, I do not wish to be understood as
20 intending to limit it thereto, as the same may be variously modified and altered without departing from the spirit of my invention.

What I regard as new and desire to secure by Letters Patent is:

1. In a powder receptacle, the combination of a bottom member having an upturned peripheral flange, a band section having a bead with which said flange engages to permanently hold said member and section together, a diaphragm having a filling opening connected with said band section and dividing the space between said bottom member and the upper level of said band section into two compartments, the lower one for powder and the upper for a powder puff, and a cover for the other end of said band section.

2. In a powder receptacle, the combination of a bottom member having an upturned peripheral flange, a band section hav-

ing an outer bead with which said flange engages to permanently hold said member and section together, a diaphragm having a filling opening connected with said band section and dividing the space between said bottom member and the upper level of said band section into two compartments, the lower one for powder and the upper for a powder puff, and a cover for the other end of said band section adapted to be snapped into place.

3. In a powder receptacle, the combination of a concaved bottom member having an upturned peripheral flange, a band section permanently secured to said bottom member by said flange, a diaphragm having a filling opening integrally formed with the band section and concaved oppositely from the bottom member to form a chamber therebetween to contain powder, and a cover member adapted to engage the upper part of said band section to close the opening therein.

4. In a powder receptacle, the combination of a concaved bottom member having an upturned peripheral flange, a band section permanently secured to said bottom member by said flange, a diaphragm having a filling opening integrally formed with the band section and concaved oppositely from the bottom member to form a chamber therebetween to contain powder, and a cover member adapted to engage the upper part of said band section to close the opening therein, said cover comprising a concaved member having an upturned flange, and a frame member fitting within said concaved part and held in position by said flange and adapted to hold a mirror or the like between it and said cover.

5. In a powder receptacle, the combination of a concaved bottom member having an upturned flange, a band section telescoping within said upturned flange, a diaphragm having a filling opening integral therewith adapted to form with said concaved bottom a chamber for powder, a plurality of projections at the upper part of said band member, and a cover adapted to close the opening of said band member comprising a concaved member having an upturned flange, and means carried thereby adapted to coact with said projections for holding the cover in place.

JOSEPH KOMOROUS.
